UNITED STATES PATENT OFFICE.

JOSEPH J. HAUCK AND WILLIAM H. WHYTE, OF CALUMET, MICHIGAN.

LOCOMOTIVE-WHEEL-BLOCKING DEVICE.

1,356,358.

Specification of Letters Patent. Patented Oct. 19, 1920.

Application filed November 28, 1919. Serial No. 341,026.

To all whom it may concern:

Be it known that we, JOSEPH J. HAUCK and WILLIAM H. WHYTE, citizens of the United States, residing at Calumet, in the county of Houghton and State of Michigan, have invented certain new and useful Improvements in Locomotive-Wheel-Blocking Devices; and we do declare the following to be a full, clear, and exact description of the invention, such as will enable others skilled in the art to which it appertains to make and use the same.

This invention relates to improvements in wheel chocks for blocking locomotives.

15 The primary object is to provide a wheel chock including a pair of blocks so connected as to be normally retained at a maximum point of separation and adapted to be placed in operative position without necessitating raising the wheel to be chocked.

With the above and other objects in view the invention consists of certain novel features of construction and the combination and arrangement of parts as will be more 25 fully described and claimed.

We attain these objects by the construction illustrated in the accompanying drawings, in which—

Figure 1 is a top plan view of the wheel 30 chock;

Fig. 2, is a side elevation, with parts in section; and

Fig. 3, a detail section of one of the blocks.

Similar numerals of reference designate 35 similar parts throughout the several views.

Reference is now had to the drawings in which wheel W is shown positioned on a rail R.

The chock broadly includes a pair of 40 tapered blocks 1 connected by means of a frame 2 which may be of any suitable shape or form but is preferably constructed of a strip of spring metal bent into substantially U-shape and normally retaining the blocks 45 at the maximum point of separation. Although other means for compressing the spring may be employed we preferably provide a bar loosely carried by the spring arms 3 and co-acting with a suitable lever 50 4 or the like, to perform said function.

The chock blocks 1 are formed of any suitable metal and are provided with inwardly tapered upper faces for engaging the periphery of a wheel. The lower faces of the 55 blocks 1 are provided with transverse teeth

5 adapted to bite or grip the rail when in operative position.

While the block may be otherwise connected, we preferably employ a substantially U-shaped spring metal frame 2 whose arms 3 60 are suitably secured to the outer faces of the chock block by screw bolts 7 or the like. The natural tendency of the arms is to separate to a certain degree and thereby retain the blocks in their maximum spaced relation. 65

In order to retain the blocks spaced in approximately the proper relation for engaging a wheel, we have provided each arm 6 with a slot 8 at a point adjacent the chock 70 block 1, said slots being adapted to receive a bar 9, one end of which is passed through one slot and retained therein by suitable means, while the other end is passed through the other slot and provided with a cam lever 75 4. Fig. 1 shows the cam lever in operative or locking position and when the lever is rotated 180° it is obvious that the arms are allowed to expand, and this expanded position may be varied by adjusting a pin 11 80 in the apertures 12 in the bar at the end opposite the lever.

The pin 11 is formed with a shoulder 13 to prevent it passing entirely through one of the apertures 12 and is permanently carried 85 by the adjacent arm through the chain connection 14 which is suitably secured to the arm and pin.

In operation, the wheel chock having previously been adjusted to the approximate 90 size of the wheel, the device is moved laterally taking under the wheel rim and then the cam lever is turned to the position indicated in Fig. 1, thereby positively locking the wheel against movement. It is very apparent that this structure eliminates the necessity of lifting the wheel to be chocked. 95

From the foregoing description taken in connection with the accompanying drawings, the construction and operation of the invention will be readily understood without requiring a more extended explanation. 100

Various changes in the form proportion and minor details of construction may be resorted to without departing from the principle or sacrificing any of the advantages 105 of the claimed invention.

We claim:

1. A wheel chock comprising a substantially rigid unitary structure to be applied 110

to a wheel from one of its sides and including a substantially U-shaped frame to be positioned horizontally, opposed chock blocks at the ends of the frame and means for moving said blocks relatively to each other.

2. A wheel chock comprising a pair of chock blocks, a pair of connected supporting arms connected at their ends to said blocks and projecting horizontally and laterally therefrom in the same direction, the opposite sides of the blocks being free and unconnected to permit of the ready application of the device to the wheel from one side of the latter, and means for moving one arm relative to the other to vary the space between the blocks.

3. A wheel chock comprising a substantially U-shaped spring member, opposed chock blocks carried by the arms of said spring member, means for moving one arm relatively to the other to vary the space between the blocks.

4. In a wheel chock, a pair of chock blocks to receive a wheel therebetween, a resilient carrier for said blocks to yieldably retain them in their maximum separated positions, and means for adjusting the carrier and moving and locking the said blocks into engagement with a wheel.

5. In a wheel chock, a pair of chock blocks to receive a wheel therebetween, a substantially U-shaped spring connecting said blocks to normally separate them to the maximum point, and means for compressing said spring to move and lock the blocks into engagement with a wheel.

6. In a wheel chock, a pair of chock blocks to receive a wheel therebetween, means connecting said blocks to normally separate them to the maximum point, a cam lever, and means coacting with the cam lever and connecting means for moving and locking said blocks into engagement with a wheel.

7. In a wheel chock, a pair of chock blocks to receive a wheel therebetween, a substantially U-shaped spring having its arms secured to said blocks, a bar extending from one arm of said spring and having its other end slideable through the other arm, and a cam lever mounted on the free end of said bar engaging the outer face of the adjacent arm and adapted to be operated to compress said spring to move and lock the blocks into engagement with a wheel.

8. In a wheel chock, a pair of chock blocks to receive a wheel therebetween, a substantially U-shaped spring having its arms secured to said blocks, said arms having a pair of longitudinally aligned openings, a bar connecting said arms and having its ends projecting through said openings, one end of said bar having a series of apertures, a pin adapted for reception in one of said apertures, a cam lever carried by the other end of said bar and adapted to be operated to compress the arms and move the blocks into engagement with a wheel.

In testimony whereof we have hereunto set our hands.

JOSEPH J. HAUCK.
WILLIAM H. WHYTE.
